UNITED STATES PATENT OFFICE.

JOHN H. MILLER, OF PINEVILLE, KENTUCKY.

CAR-OPERATED MINE DOOR.

Application filed January 19, 1924. Serial No. 687,292.

To all whom it may concern:

Be it known that I, JOHN H. MILLER, a citizen of the United States, residing at Pineville, in the county of Bell and State of Kentucky, have invented new and useful Improvements in Car-Operated Mine Doors, of which the following is a specification.

This invention relates to door operating mechanism and has for its object the provision of means mounted along a mine track and engageable by a car traveling thereover whereby to automatically open the safety doors commonly provided, the device having the great advantage of obviating all necessity for manual operation.

An important object is the provision of an apparatus of this character including operating means engageable by the car wheels, other operating means being provided to insure action in the event of failure of the wheel operated means.

Yet another object is the provision of a device of this character provided with means for automatically reclosing the doors after the car has passed through.

An additional object is the provision of structure for this purpose which will be simple and inexpensive in manufacture, and installation, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a plan view of the complete device, the doors being shown closed in full lines and open by dotted lines,

Figure 2 is a longitudinal section,

Figure 3 is a detail section on the line 3—3 of Figure 1,

Figure 4 is a detail cross section through one of the actuating members,

Figure 5 is a detail section on the line 5—5 of Figure 1,

Figure 6 is a detail section on the line 6—6 of Figure 1,

Figure 7 is a detail perspective view of one of the door carried brackets.

Figure 8 is a detail section on the line 8—8 of Figure 1.

Referring more particularly to the drawings the letter A designates a track including the usual ties B carrying the rails C.

The letter D indicates the bulkhead having a door opening adapted to be closed by doors E which are hinged as shown at the side edges of the opening.

The invention consists in providing means for opening and closing these doors automatically, and in carrying it out, I provide supports 10 stationarily mounted at opposite sides of the door way and having pivoted thereto, at 11, a sectional ramp 12 including sections 13 and 14, hingedly connected as shown at 15. The sections 13 ascend while the sections 14 descend, and the free ends of the sections 14 are slidable upon wear plates 16 which are formed with slots 17 for the passage of depending guides 18 carried by the sections.

Secured upon a tie at each side of the door way is a plate 19 having pairs of spaced ears 20 between which are pivoted arms 21 carried by a rock shaft 22 which projects beyond one side of the track and which has its projecting end equipped with a long arm 23 having a weight 24 slidably adjustably mounted thereon. On the underside of each ramp section 13 is a forked element 25 within which is pivoted at 26 a depending link 27 pivotally connected at 28 with an arm 29 projecting from the rock shaft 22 so that when the ramp is depressed by passage of the car along the track, the effect will be to rock the shaft 22.

Carried by the hinged edge of each door is a curved bracket 30 having a forked end 31 within which is pivoted one end of a reach rod 32 having a turn buckle 33 interposed therein for adjusting purposes. Carried by each rock shaft 22 is an arm 34 pivoted at 35 to an elongated yoke 36 which has its bight portion formed with a hole. The reach rods 32 extend through these holes and along the yokes 36 and through cross members 37 in the yokes which constitute guides. Within the yokes, the rods 32 are encircled by coil springs 38 which bear against the bight portions of the yokes and against adjusting nuts 39 threaded onto the rods.

The doors carry oppositely extending brackets 40 at the hinged edges thereof connected by a bridle bar 41 which insures simultaneous operation of the doors.

In the operation of the device up to this point, it will be seen that when a car approaches the door way from either side, the passage of the car over a ramp will

cause depression thereof and consequent rocking of the shaft 22 as above described. When either shaft 22 is thus rocked, it is apparent that the arm 34 will swing away from the doors so that a pull will be applied to the yoke 36. This pull is transmitted to the associated rod 32 and as this rod is connected with the bracket 30 on a door, the result will be that the doors will 10 be swung into open position as indicated by dotted lines in Figure 1 so that the car may pass through. The weights 24 operate to return the parts to normal position.

Attention is called to the fact that the 15 ramp sections are angular in cross section and that they are located immediately against the rails, the sections being formed with upstanding flanges 42 which project above the rails so as to be engaged by the 20 treads of the wheels. This specific construction is preferred as it obviates any necessity for providing an element on the car to engage the ramp.

To insure operation in the event of failure 25 of the ramp structure, I make use of an auxiliary operating mechanism. This feature involves the provision of upstanding posts 43 located at the opposite sides of the track at one side of the door way. Hinged upon 30 these posts are bars 44 which normally extend in obstructing relation across the track and which are equipped with buffer rods or wear members 45 which will prevent damage when the bars are engaged by a car. It 35 might also be mentioned in passing that the doors E are likewise equipped with similar buffer bars 46 for the same purpose.

The numeral 47 designates supporting sills which extend from the posts 43 to the 40 bulkhead D, which sills form supports for levers 48 pivoted thereon as shown at 49. These levers are pivotally connected at one end with links 50 which are pivoted to brackets 51 on the bars 44. Pivoted at 52 45 on the sills are other levers 53 which are pivotally connected at one end with the adjacent lever 48 by means of links 54, and which have pivoted to their other ends reach rods 55 equipped with turn buckles 56 and connected with brackets 57 on the doors.

In case the track mechanism fails to operate, it is apparent that a car approaching the door-way from that side equipped with the bars 44, will strike against these bars and 55 swing them outwardly as indicated by dotted lines in Figure 1. When this movement occurs, the link and lever mechanism

will operate to swing the doors E into open position. Quite naturally, it will be seen that when the doors are opened by the ramp 60 mechanism, the bars 44 will be swung even though they are not engaged by the car.

From the foregoing description and a study of the drawings it will be apparent that I have thus provided a simply constructed and easily installed mechanism for automatically opening the safety doors upon the approach of a car from either direction so that it will be unnecessary for the operator of the car to open the doors manually. 70 The mechanism really consists of comparatively few parts which may be of very rugged construction so as to withstand hard service without derangement.

While I have shown and described the 75 preferred embodiment of my invention it is of course to be understood that I reserve the right to make such changes in the form, construction and arrangement of parts as will not depart from the spirit of the invention 80 or the scope of the subjoined claims.

I claim:

1. Means for operating hingedly mounted mine-doors along a track way, comprising 85 rock shafts journaled across the track way at opposite sides of the door opening and carrying arms, sectional hingedly connected ramps extending along the track way and connected with said arms, said ramps being positioned for engagement by the wheels 90 of a car passing along the track, brackets on the hinged edges of the doors, means connecting the doors for effecting simultaneous operation, reach rods connected with said 95 brackets, and other arms on the rock shafts connected with the reach rods, said last named connection consisting of yokes carried by the last named arms and through which the reach rods are slidably, and yield- 100 able tension means within the yokes.

2. Operating means for hinged safety mine-doors extending across a track way, comprising supports along the track way at opposite sides thereof, horizontal bars pivoted on said supports and obstructing the 105 track way for engagement by a car, levers pivoted on the supports and connected with said bars, other levers pivoted on the supports and connected with the first named levers, and reach rods pivotally connected with the second named levers and with the doors.

In testimony whereof I affix my signature.
JOHN H. MILLER.
